UNITED STATES PATENT OFFICE.

EBEN WILLIS, OF COLTON, NEW YORK.

SAP-SPOUT.

SPECIFICATION forming part of Letters Patent No. 606,613, dated June 28, 1898.

Application filed April 8, 1898. Serial No. 676,941. (No model.)

To all whom it may concern:

Be it known that I, EBEN WILLIS, a citizen of the United States, residing at Colton, in the county of St. Lawrence, State of New York, have invented certain new and useful Improvements in Sap-Spouts, of which the following is a specification, reference being had therein to the accompanying drawings.

This invention relates to sap-spouts, and more particularly to improvements upon the spout disclosed in Patent No. 455,784, granted me July 14, 1891.

The invention has for its object to improve the construction of the entering end of the spout, so that the same will not come into contact with the vertical pores of the wood which have been severed, as such contact would materially reduce the flow of sap from the open pores.

The invention has for a further object to provide anchoring-lugs which will retain the spout in the hole bored in the tree when the sap freezes in said hole, and thus prevent the sap from starting out, and thereby obviating any leakage about the plug portion of the spout.

Other objects and advantages of the invention will hereinafter appear in the following description, and the novel features thereof will be particularly pointed out in the appended claims.

In the drawings, Figure 1 is a perspective of the sap-spout. Fig. 2 is a longitudinal section of the same as applied to a tree. Fig. 3 is a top plan view, and Fig. 4 is an elevation of the inner end of the spout.

Like letters of reference indicate like parts throughout the several figures of the drawings.

The letter A designates the body of the spout, which may be formed of any desired material, although preferably of malleable white iron and suitably plated or tinned to prevent corrosion from the exposure to which it is subjected. The discharge end of the spout is provided with a depending lip A' for the purpose of guiding the drip from the channel of the spout. The discharge end of the spout is also formed as an open channel, although it may be inclosed, as shown in my former patent. Adjacent to the entering end of the spout a hook B is provided, which may

be formed separate from or integral with the body A of the spout, and this hook is provided with a flat bearing-surface B' upon its rear to rest against the body of the tree to which the spout is applied and also with a rib B², surrounding the spout, to limit the inward movement of the entering end and to support the spout by contact with the adjacent body of the tree. The lower end of the depending hook is provided with a flattened surface B³ upon its inner curve, which will bear upon the can or bucket supported thereupon, and thus prevent swaying or accidental blowing off of the bucket during a high wind. It will be seen that this hook will enter the usual round hole in the sap-bucket to perform the functions just described.

At the inner side of the rib B² a circular plugging portion is provided, which fits tightly within the hole bored in the tree to prevent the escape of sap from the hole except through the channel provided in the spout. The opposite walls of this portion are cut away toward the inner or entering end of the spout until they leave only inner extensions or bars C', which tightly fit the side walls of the hole. These opposite bearing extensions C' are connected by the web C², and extending in opposite directions from this web are anchoring-lugs D, which are of less diameter than the diameter of the flanges C', and consequently do not come into contact with the walls of the hole.

In boring the usual hole in a sap-bearing tree the vertical pores constitute the sap-feeding area, while the pores at the sides of the hole where the extensions C' will bind against are uncut pores, and thus they in no manner limit the flow of the sap. The plug at the outer end of the entering end merely bears upon that portion of the hole directly adjacent to the bark, and from which little or no sap will feed. Under normal conditions the retaining extensions C' and plug portion C, when driven into the hole until the rib B² rests against the bark, will firmly retain the spout in position when the sap-bucket is carried thereby. When the sap in the hole freezes in extremely cold weather, it is obvious that there will be such a contraction of the parts constituting the securing means for the spout that the same will become loose

and liable to be drawn out by the weight of the bucket or to leak when the sap begins to thaw. To effectually prevent this the anchoring-lugs D are provided, which are frozen 5 in the sap contained in the hole, and thus prevent the sap-spout from starting out or loosening, whereby all leakage is prevented. As previously described, the anchoring-lugs are of less diameter than the bearing extensions 10 or bars, and consequently do not in any way interfere with the flow of sap from the vertical pores of the tree.

Having described my invention, what I claim, and desire to secure by Letters Patent, 15 is—

1. A sap-spout provided with a longitudinal channel, a depending hook from said spout, a plugging portion at the rear of said hook, bearing extensions from said plugging 20 portion at the sides thereof and of equal width therewith, and anchoring-lugs projecting from said extensions in opposite directions and of less width than said extensions; substantially as specified.
2. A sap-spout provided with a longitudi- 25

nal channel, a cylindrical plugging portion at the rear of said channel, horizontal extensions merged into and of equal width with said plugging portion, a web connecting said extensions at their inner end, and oppositely-extending anchoring-lugs of less width than said plugging portion; substantially as specified. 30

3. An improved sap-spout consisting of a body portion with a depending lip at its outer 35 end, a depending hook having a flattened inner face, a rib upon the face of said body portion in the plane of said hook, a cylindrical plugging portion, extensions extending therefrom at the sides thereof, a web connecting 40 the inner end of said extensions, and oppositely-extending lugs carried by said web and of less width than the plugging portion; substantially as specified.

In testimony whereof I affix my signature 45 in presence of two witnesses.

EBEN WILLIS.
